US0D1111811S

(12) **United States Design Patent** (10) **Patent No.:** **US D1,111,811 S**
(45) **Date of Patent:** **** Feb. 10, 2026**

(54) **PACKAGING WITH ORNAMENTATION**

(71) Applicant: **The Procter & Gamble Company**,
Cincinnati, OH (US)

(72) Inventors: **Gina Barattieri Tesnar**, Newport, KY
(US); **Gabriel Fernandes**, Hamburg
(DE)

(73) Assignee: **The Procter & Gamble Company**,
Cincinnati, OH (US)

(**) Term: **15 Years**

(21) Appl. No.: **29/897,037**

(22) Filed: **Jul. 11, 2023**

(30) **Foreign Application Priority Data**

Jan. 12, 2023 (WO) WIPO127445

(51) **LOC (15) Cl.** **09-01**

(52) **U.S. Cl.**

USPC **D9/529**
